UNITED STATES PATENT OFFICE.

CHARLES L. GOODRUM, OF URBANA, OHIO, ASSIGNOR, BY MESNE ASSIGNMENTS, TO
WESTERN ELECTRIC COMPANY, INCORPORATED, A CORPORATION OF NEW YORK.

LOCKING MECHANISM FOR IMPULSE-TRANSMITTERS

1,223,382.

Specification of Letters Patent. Patented Apr. 24, 1917.

Application filed May 1, 1909. Serial No. 493,395.

To all whom it may concern:

Be it known that I, CHARLES L. GOODRUM, a citizen of the United States, residing at Urbana, in the county of Champaign and 5 State of Ohio, have invented certain new and useful Improvements in Locking Mechanism for Impulse-Transmitters, of which the following is a specification.

My invention relates to improvements in 10 devices and circuits for impulse transmitters or calling devices. The construction of the devices and arrangement of the circuits being especially adapted for use with automatic telephony being, however, in its 15 broader application, capable of use in other associations.

The object of my invention is to provide 20 means for automatically locking an impulse transmitter or signaling device whenever the circuit over which the impulses are to be transmitted is incomplete and retaining the same locked until such a time as the circuit is in proper condition to receive such impulses or signals.

25 A further object of my invention consists in means to apply ringing current to the called subscriber's line in a two wire automatic telephone system by rapidly interrupting the line circuit at the calling subscriber's station thus placing the application of ringing current to the called subscriber's line under the direct control of the calling party.

My invention consists primarily in an improved locking device for an impulse transmitter adapted to be operated to unlock the transmitter by electrically operated devices so that when a current of a proper strength to give effect to the impulses to be transmitted passes through the impulse transmitter, the said device will be unlocked, the construction being such that under any other condition the impulse transmitter will be locked against operation. When the impulse transmitter is connected to the switching or receiving devices, (such as a selector or connector switch), the current flowing in the circuit will be of sufficient strength to unlock the transmitter so that it can be used 50 to transmit impulses to the office switches to set up the connection. After the connection has been extended through the selecting switches to the desired subscriber's line the impulse transmitter remains unlocked. Any

operation of the impulse transmitter, after 55 the connection has been extended to the called subscriber's line, will connect ringing current to the line of the called subscriber.

In the accompanying drawings I have 60 illustrated my invention in connection with 65 circuits of an automatic telephone exchange, the arrangements being such that the impulse transmitter will be locked until the apparatus to be acted upon by said impulse transmitter is brought into circuit. 65

In the said drawings, Figure 1 is a diagrammatic view illustrating a single calling station in connection with automatic switching mechanism, (such as is generally known as a finder switch) with the apparatus necessary to cut through the lines from the calling station to the apparatus, (such as a selector or connector switch) which would be operated upon by the impulse transmitter. Fig. 2 is a diagrammatic view illustrating a 70 subscriber's station and showing the mechanical arrangement of the locking devices for a calling device having a rotating dial. Fig. 3 is a diagrammatic view of a called station showing the arrangement of a part 75 of the exchange mechanism used in connection with the switching mechanism for signaling and for releasing the lines already connected. 80

In the diagrammatic view Fig. 1, I have 85 shown the simplest form of circuit, one calling subscriber, one automatic switching device with its accompanying relay apparatus necessary to cut the line through to a called station or to a selector or connector switch, 90 either of which may be used in connection with the impulse transmitter.

Like characters of reference indicate like parts in the several views.

In the said drawings, A represents a calling sub-station, B represents the automatic switching mechanism, and C represents a called station. 95

At the station, A, in Fig. 1, I have illustrated only the signaling or impulse mechanism and it will be understood that when applied to a telephone exchange such apparatus would be supplied at each subscriber's station, also that talking instruments and circuits usually employed in said station 100 would be supplied as shown in station C. 105

At the calling station A, in Fig. 1, a represents a circuit breaker of an impulse trans-

mitter which may consist of a metallic disk having a portion, a^1 , thereof of insulating material adapted to be revolved so as to contact with wipers, a^2 a^3 , which are arranged in the circuit of the subscriber's station. a^4 is a dial which is connected by suitable gearing, a^5 , to the circuit breaker, a , and said dial, a^4 , is normally locked by a locking lever, a^6 , which engages said dial in a suitable manner so as to hold the same normally locked. This locking lever, a^6 , is adapted to be operated to unlock the dial by an electromagnet, a^7 , also placed within the subscriber's circuit. The receiver hook, a^8 , is adapted in the usual manner, when the receiver is removed, to make connection with the line, l , which, with its mate, m , constitutes the subscriber's line to the central station. A circuit is established from l , through the receiver hook, a^8 , by wire 1 (one), through wipers, a^2 a^3 , and thence by line 3 to mate m . The line, l , and its mate, m , terminate on contact l^1 and m^1 , it being understood that there would be similar contacts for each subscriber's line which enters the exchange and common to the same switching mechanism. Each subscriber's line is provided at the central exchange with a line relay, c , and a cut-off relay, d , and when the circuit is closed at a subscriber's station by operating the receiver hook, a^8 , a circuit is established through the line relay, c , as follows: from the hook, a^8 , through the line l , wire 4, circuit breaker, d^1 , contact, d^2 , wire 5, to one side of coil c , thence through wire 6, battery 7, wire 8, the opposite side of coil c , wire 9, contact d^3 , circuit breaker d^4 , wire 10 to the opposite side or mate, m , of the line.

In this particular adaptation of my locking device the battery, 7, of, say, 20 volts, is not of sufficient potential to operate the relay, a^7 , although this battery is, by the operation of the closing of the circuit just named, thrown directly on the line and through the coil, a^7 . The battery, 7, however, is sufficiently strong to operate the relay, c , which causes it to pull up its armature and close a circuit as follows: from ground at e^1 , through circuit breaker e^2 , contact e^3 , wire 11, switch arm 12, contact 13, wire 14, contact 15, arm 16, line 17, to relay e , wire 18, battery 20 and to ground at e^1 . The battery 20 is of much higher potential than the battery 7, being preferably about 60 volts, and is the battery used for operating the switching apparatus at the exchange and also for supplying talking current. The circuit just traced will energize the relay, e . The effect of energizing the relay, e , is to close the circuit breakers, e^2 and e^3 . The closing of the circuit breaker, e^2 , establishes the following circuit: from ground at 21, through wire 22, contact h^2 , circuit breaker h^1 , wire 25, branch 26, circuit breaker e^2 , contact e^4 , wire 27, wire 74, to relay f , wire 34, wire 35, wire 36,

battery 20 and to ground at e^1 . This energizes the relay, f , and establishes a circuit as follows: ground at 37, wire 38, circuit breaker f^1 , contact f^2 , wire 39, circuit breaker e^5 , contact e^6 , wire 40, wire 41, to motor magnet g , wire 42, battery 43, wire 44, to ground at 45. A branch circuit is also established from wire 40, by wire 46, to relay h , wire 47, and thence by wire 35 and wire 36 to battery 20 and ground at e^1 , thus energizing the magnets g and h . The magnet, g , is the motor magnet for operating the switching mechanism which is to connect with the calling subscriber's line and which would be known as a finder switch.

The energizing of the magnet, g , breaks the circuit of the relay, e , at the contacts, 15 and 16, it also moves the operating spring for the switching mechanism back one notch. The circuit for the motor magnet, g , however, passes through the circuit breaking contacts, e^3 e^5 , so that when the magnet, g , is deenergized it, in turn, deenergizes the motor magnet, g , which permits the step-up devices to move the finder switch one step. The relays, f and h , are what are known as slow relays and their operation is retarded so that if the deenergizing of the relays, e and g , is quickly followed by closing their circuits and energizing the same, the magnets, f and h , will not become deenergized but will hold over, holding their armature contacts in the position assumed by them by reason of the electro-magnetic force of the relays.

It will be understood that each step of the finder switch causes the switch arms to move to a different set of contacts and each set of contacts is connected with the lines of some subscriber. In the normal position the switch arms do not rest upon any line contacts. The first movement of the switch, however, passes the switch arms over onto the contacts of some line. The circuit breaking contacts, 12 and 13, through which the circuit to the relay, e , passes, are held closed by a projection, b , on the switching mechanism, but at the first step of said switching device this projection, b , moves away from the arm, 12, and opens the contacts at 12 and 13, so that the further operation of the relay, e , must be attained by current secured from some other source, which I will now proceed to describe. The finder switch is preferably provided with four arms or wipers, b^1 , b^2 , b^3 , b^4 , the wipers, b^1 and b^2 , are adapted to contact with the terminals, l^1 and m^1 , of the lines and mates of the respective subscribers, and the wipers, b^3 and b^4 , are adapted to contact with terminals of local operating circuits to be described. These wipers will preferably be placed one above the other on a vertical axis, being shown in diagram in the accompanying drawings.

I have shown one set of terminals only which contact with the wipers, b^3 and b^4 , and these are c^5 and d^5 , it being understood that there will be a set of terminals, c^5 d^5 , 5 for each set of line terminals, l^1 and m^1 . Assuming now that the finder switch has stepped up one step and the wiper, b^4 , has ~~contacted~~ with the terminals, c^5 , on a line whose relay, e , has not been operated, a circuit 10 may then be traced from ground c^1 , through circuit breaker c^2 , contact c^4 , wire 48, to terminal c^5 , wiper b^4 , line 49, wire 25, circuit breaker h^1 , (the relay, h , being held up) contact, h^2 , wire 51, wire 14, contact 15, 15 circuit breaker 16, wire 17, relay e , wire 18, battery 20, to ground. Thus, again energizing the relay, e , which would repeat the operation of energizing the motor magnet, g , which in turn breaks the circuit of the relay, 20 e , at 15 and 16, causing the said relay to be deenergized, thus deenergizing the motor magnet, g , and causing the finder switch to make another step. This operation will be continued so long as the wiper, b^4 , continues 25 to find ground through the circuit, as indicated by wire 48, circuit breakers, c^2 c^4 , and ground at c^1 . When, however, the circuit at c^2 c^4 is broken, as it will be whenever the line relay, e , of any subscriber's line is energized, then the wiper, b^4 , will not find ground and the relay, e , will not be energized and the finder switch will, therefore, stop on that line, thus connecting the subscribers' lines, l and m , through terminals, l^1 30 and m^1 , to wipers, b^1 b^2 , and thence by wires, l^2 and m^2 . The line, l^1 , passes through contact, 52, circuit breaker, 53, and out to the called station or to some other switching device, such as a selector or connector switch, 35 while the line, m^2 , passes through contact, 54, circuit breaker 55, in a similar way to the called station or some other switching device. From l^2 a branch, 56, leads through a relay, j , by wire, 57, to ground at j^1 . A 40 branch, 58, from m^2 passes through the other coil of the relay, j , thence by wire, 59, of wire, 36, to battery 20 and to ground at e^1 . This throws the high potential battery, 20, directly on the subscriber's line. The circuit 45 may be traced from ground at e^1 , battery 20, wire 19, wire 36, wire 59, one side of the relay, j , wire 58, to one side of the line m^2 , thence through the wiper, b^1 , terminal m^1 , line m , lock coil, a^7 , at the calling subscriber's station, two wipers a^2 a^3 , impulse device a^1 , line l , receiver hook, a^8 , line l terminal b^1 , wiper b^2 , line l^2 , branch 56 other side of the relay and to ground at j^1 , the battery 20 being of sufficient voltage to operate the lock coil, a^7 , the lock lever, a^6 , is removed from the dial, a^4 , and the transmitting device is ready for operation.

The moment that the wiper, b^4 , fails to find ground upon the terminal, c^5 , as before described, the wiper, b^3 , contacts with the

terminal, d^5 , and closes the circuit as follows: from ground at c^6 , through wire 60, battery 7, wire 61, relay d , terminal d^3 ; wiper b^3 , line 62, contact 63, circuit breaker f^1 , line 38 and to ground at 37. This energizes the relay, d , and cuts off both sides of the coil of the line relay, e , the circuits for which pass through the circuit breakers, d^1 , d^2 , d^3 , d^4 as heretofore described, thus cutting out the relay, e , from the line and leaving the relay, d , energized so long as the wipers, b^3 , remain on contact, d^5 . In the description thus far it is assumed that the lines, l^2 and m^2 , are to be connected with the devices to which impulses are to be transmitted. The impulse transmitter at the calling station is now free to be operated and may be operated in such manner as is necessary, either to establish connection through other suitable switching mechanism with the subscriber or to send signals to a station which may be connected directly on the lines, l^2 and m^2 . In releasing the line the subscriber at l^1 hangs up the receiver which breaks the connection between the receiver hook, a^8 , and line, l . This breaks the circuit, previously described, (Fig. 1) through the relay, j , which causes it to be deenergized, and the circuit breaker, j^2 , which is operated thereby, closes against the contact j^3 , establishing the following circuit: from ground at 64, through circuit breaker j^2 , contact j^3 , wire 65, circuit breaker h^1 , contact h^5 , line 63, contact 67, circuit breaker 68, wire 69, release magnet k , wire 70, battery 43, wire 44, to ground at 45. This release magnet, k , becomes thus energized and its armature is arranged to disengage the pawls, the holding pawl and the operating pawl on the finder switch thus permitting said switch to return to its normal position. The energizing of the magnet, k , also closes the following circuit: from ground at 71, contact 72, circuit breaker 73, line 74, through relay f , wire 34, wires 35, 36, battery 20 to ground at b^1 . This opens the line contacts, 52, 53, 54, 55, so as to prevent the wipers from finding ground in passing over the contacts on their return to normal. In returning to normal the contact, b , on the switching device operates the circuit breakers, 12 and 67, to close the circuit at 13 and break the circuit at 67, thus deenergizing the magnet, k , and restoring the starting circuit for the relay, e .

Assuming the line, l^2 , is now connected either to a called station by means of an intermediate switching device or direct, I will now proceed to describe the signaling circuits (see Fig. 3): The line l^2 passes through the contact n^3 , circuit breaker n^2 , to line l^3 , and thence to the called subscriber's station, C, which, with the receiver hook in its normal position, will have the bell or signaling device, o , bridged across the line in the reg-

ular manner. The line, m^2 , will be connected through the circuit breaker, n^4 , n^5 , to line, m^3 , in a similar manner.

- When this form of ringing circuit is employed the circuits for the relay j in Fig. 1 and the release circuit controlled thereby are modified as shown in Fig. 3, in which the relay corresponding to j , is marked t . The release circuit 65 is passed through contact 10 p^3 and spring p^2 of a relay p , the release circuit in this case being from wire 65, contacts p^3 , p^2 , wire 79, to contacts t^2 and t^3 (which correspond with j^2 and j^3 in Fig. 1), and thence by wire 75 to ground. The relay 15 p is controlled by the forward contact of relay, t , (j in Fig. 1), and when said relay is energized it energizes relay p over the circuit from ground by wire 75, spring t^2 , contact t^4 , wire 76, relay p , wire 74, battery 20, 20 and wire 78 to ground at t^1 . The relay p is a slow relay and when energized, breaks the release circuit at p^3 and closes its spring p^2 against the contact p^1 . This closes the circuit for relay n through wire 80, relay n , wire 77, battery 20, wire 78, wire 75, spring t^2 , contact t^3 , and wire 79 to spring p^2 . When relay t is energized therefore, relay p will be energized and the circuit thereby closed at contact t^4 . When relay t is deenergized, relay n will be energized over the circuit closed at back contact t^1 , providing that the spring p^2 is on the front contact p^1 . Relays p and n are both slow relays so that relay p will hold up momentarily after relay t is deenergized, which permits relay n to receive current by deenergizing relay t and before relay p allows its armature to drop back. Inasmuch as relay t is a normal relay which will respond to impulses of current, its armature will alternately open and close the circuits for relays p and n at the back and front contacts p^3 and p^4 , a series of impulses over lines l^2 , m^2 , will keep both of these relays p and n energized. This will cause the 45 release circuit to be broken at p^3 and cause ringing circuit to be applied to the called station whenever the impulse transmitter at the calling station A is operated. These impulses will have the effect of energizing the slow relays, p and n , and holding their armatures, and closing the circuit breakers, n^2 and n^3 , on the contacts, n^1 and n^4 , which contacts are the terminals for the opposite sides of a generator circuit, as indicated at r . 50 The result will be that so long as the impulses continue and the relays, n and p , continue to hold up, the generator will be included in the line, l^3 and m^3 , and will cause the signaling device, o , to be operated and 55 also, as soon as the impulses cease, the relay, t , will be again energized, which will break the circuits to the relay, n , causing it to be deenergized and interrupt the ringing circuit. 60
- 65 When the calling subscriber breaks the

circuit at the receiver hook, a^8 , the magnet, t , is deenergized, which, in turn, deenergizes the magnet, p , and closes the release circuit, heretofore described, from the line 65, through the contacts, p^2 and p^3 , line 79, contacts t^2 and t^3 , and wire 75 to ground, the relay, p , and the additional circuit breaker in the release circuit being provided so that the release magnet shall not be operated by the vibrations of the circuit breaker, t^2 , caused by the impulses on the line by the impulse transmitter. 70 75

In practice all the circuits here will be metallic circuits and where ground is referred to it is to be understood that this indicates simply one terminal of the battery which will be connected by metallic circuit either by a suitable battery wire or common return. 80

Having thus described my invention, I claim:

1. The combination with an impulse transmitter, a normally open subscriber's line into which said transmitter may be included, a locking device for the transmitter, 90 an electromagnet adapted to be connected into the subscriber's line for operating the said locking device to unlock the transmitter, an impulse receiver and means for establishing a connection with said impulse receiver upon closing the subscriber's line, a source of electric energy sufficient to operate the electromagnet to unlock said transmitter, and means for connecting said energy onto the subscriber's line when the impulse receiver is in circuit, substantially as specified. 95

2. In an automatic telephone system, a calling subscriber's station, an automatic mechanism for connecting said calling subscriber's station to a called subscriber's station, an impulse transmitter forming a part of said mechanism for effecting said connection, a locking device for said transmitter, means associated with the connecting 110 mechanism for operating said locking device to unlock said transmitter when the same is in condition to receive impulses, a slow acting relay and a generator circuit normally disconnected from, but adapted to 115 be connected with, said called subscriber's line by said slow acting relay influenced by the impulses from said transmitter, whereby ringing impulses may be sent from said transmitter after connections have been established between the calling and called subscriber's stations. 120

3. In an automatic telephone system, two subscriber's stations, an automatic mechanism for establishing connection between the 125 same involving a calling station and an impulse transmitter, and means for establishing said connection by impulses from said transmitter, a generator circuit normally disconnected from connected stations, a line 130

relay responsive to interruptions in the line circuit, a slow relay, and a ringing relay, said ringing relay being controlled jointly by said line and slow relays to connect said generator circuit into the connected line circuit.

4. In an automatic telephone system, two subscribers' stations connected for conversation, an impulse transmitter at one of said stations and a ringer at the other station, a generator circuit normally disconnected from said connected stations, a line relay responsive to interruptions in the line circuit, a slow relay, and a ringing relay, said ringing relay being controlled jointly by said line and slow relays to connect said generator circuit into the connected line circuit.

5. In an automatic telephone system, two subscribers' stations connected for conversation, a ringer at one of said stations and an impulse transmitter at the other, a normal relay bridged on the line and having back and front contacts respectively connected in circuits with two slow relays, one of which relays controls a ringing circuit and being in turn controlled by the other

relay whereby the vibration of the armature caused by impulses through said normal relay will hold up the two slow relays and thus cause ringing current to be applied to the called station so long as impulses of current are passing through the normal relay.

6. In a signaling system, the combination of a line relay, an interrupter for controlling the actuation of said line relay, a slow-acting relay under the control of said line relay and a ringing relay under the control of said slow-acting relay and said line relay.

7. In a signaling system, the combination of a line relay, an interrupter for causing said line relay to vibrate, a slow-acting relay having a circuit closed in the actuated position of said line relay and a ringing relay having a closed circuit in the actuated position of said slow-acting relay and the normal position of said line relay.

In testimony whereof, I have hereunto set my hand this 16th day of April, 1909.

CHARLES L. GOODRUM.
